CURTAIN CRANE CONSTRUCTION

Guy W. Kirsch, Sturgis, Mich., assignor to Kirsch
Company, Sturgis, Mich.

Application July 1, 1935, Serial No. 29,345

16 Claims. (Cl. 156—19)

The objects of this invention are:

First, to provide a new and improved swinging crane for curtains or draperies or the like for windows or doorways.

Second, to provide such a swinging crane having an independent swinging ornament similar to a cornice thereon, to conceal the curtain rings on the swinging rod of the crane and provided with means connecting the ornament and the rod so that they may be swung together as a unit.

Third, to provide such a swinging crane in which the ornament is provided with a return which runs back to the wall to eliminate unsightly openings between the pivot of the crane and the wall.

Fourth, to provide such a swinging crane made up of a series of stock parts which may be used interchangeably for making up various types of cranes having various types of swinging ornaments so that without changing the various parts of the crane different ornaments may be used as desired, greatly simplifying the manufacture of such cranes which hitherto when ornamented have had the ornaments cast on the cranes, and reducing the cost of changing window treatments due to the necessity for purchasing complete new cranes when such a change is desired.

Fifth, to provide such a swinging crane in which the ornament may be used to conceal the rings of the curtain and which may be placed in close proximity to the ceiling if desired.

Sixth, to provide such a swinging crane which is easily and simply assembled and which is inexpensive and highly satisfactory in use.

Seventh, to provide a new and improved swinging crane and drapery combination which may be easily and simply assembled and in which a novel effect is obtained due to the arrangement of a swinging ornament and rod used to hold a series of ropes or cords.

Other objects and advantages pertaining to details and economies of construction and operation will appear from the description to follow. The device is defined in the claims. Preferred embodiments of my invention are illustrated in the accompanying drawings, in which:

Fig. 1 is a perspective view of my new and improved crane and ornament.

Fig. 2 is a plan view of my new and improved crane and ornament.

Fig. 3 is a rear perspective view showing the details of the construction.

Fig. 4 is a detail view of the bracket and rod construction shown partially in section.

Fig. 5 is a sectional view taken on line 5—5 of Fig. 4.

Fig. 6 is a detail plan view in section showing details of construction.

Fig. 7 is a perspective rear view of a slightly modified form of the invention.

Fig. 8 is an elevational view of a still different form of the invention.

Fig. 9 is a detail sectional view taken on line 9—9 of Fig. 8.

Fig. 10 is a view of a still different form of my invention.

Fig. 11 is a detail view of the form of the invention shown in Fig. 10.

Referring to the drawings, 1 is the bracket having the portion 2 adapted for attachment to the wall or window casing by screws extending through the holes 3. 4, 4 are parallel arms having at their free ends the vertically aligned openings 5. This member may be formed of sheet metal or in any suitable manner.

6 is a swinging ornament formed of sheet metal or the like having a decorative sheet metal design 7 applied to the front thereof and held in place by clips 8. The end 9 of the ornament 6 is fitted between the arms 4 of the bracket 1 and is provided with straps 10 bent around to form apertures adapted to register with the apertures 5 of the bracket 1. Straps 10 may be spot welded to the member 9 or otherwise affixed thereto. The extreme end portion 11 of the end 9 is turned back to form a return extending substantially to the wall 12 as indicated in Fig. 2 to close up a gap which would otherwise occur at this point. The return thus formed at 11 is of a depth to fit between the arms 4 of the bracket as shown in Fig. 3 and it is provided at the end with means for fastening a curtain return to the end 11. The particular means shown are in the form of an angle bracket 13 which is spot welded to the end 11 as shown. The bracket 13 is provided with apertures 14 which are so positioned that they fall in line with the loops of an ordinary curtain ring 141 which may be positioned on the curtain rod to receive the curtain, thus maintaining the top of the curtain level.

The other end of the ornament 6 is bent back as shown at 15 and an aperture 16 is provided through which the rod extends. The rod is made up of a pivot member 17 having a vertical shank 18 which passes through the apertures 5 and the straps 10 and is provided with a relatively horizontal portion 19 and a downwardly offset horizontal portion 20 which is connected to the portion 19 by a vertical connecting portion 21.

The portion 20 is swaged or otherwise pressed out of round as at 22 to fit tightly the curtain rod 23 which is preferably a hollow rod cut from stock material. This rod may be cut to desired length 5 and inserted through the aperture 16 and over the portion 29 of the pivot member 17 as shown. The rod then serves to support the free end of the ornament and to support a curtain hung on suitable rings such as 14.

10 Referring to Fig. 7, it will be noted that the end 115 of the ornament is not bent back as in Fig. 2 and means 116 comprising a strap having a portion extending backwardly from the ornament 106 and over the rod 23 are provided to support the free end of the ornament.

15 Referring to Figs. 8 and 9, it will be seen that there is a slight modification. The member 17 and the bracket 1 remain the same, but the ornament consists of a casting 24 which is fitted 20 between the arms 4 of the bracket and is apertured at 110 to receive the shank 18 of the member 17. Extending from the front of the bracket are a plurality of fingers 25 and on each of the fingers 25 is fitted a rod 26 which extends 25 in front of the rod 23. The rods 26 are joined by members 27 as illustrated, although this is not essential. A return is cast on the member 24 at 111. A lug 28 extends from the side of the casting 24 and is notched at 29 to 30 engage the vertical connecting portion 21 of the pivot member 17. It will be seen that when the member 17 is inserted through the apertures 5 of the bracket and the aperture 110 of the casting 24, the casting is pivoted in the bracket 1 and 35 the engagement of the notch 29 with the vertical portion 21 of the pivot member 17 joins the ornament 206 with the curtain rod so that the two will be swung as a unit. If desired, the return 111 can be eliminated.

40 Referring to Figs. 10 and 11, I show a still further modification of the invention in which the rod 23 and pivot member 17 and bracket 1 remain the same. The ornament 306 is somewhat different, consisting of a piece of strap metal 45 having one end 30 formed into a loop 31 which is vertically disposed in the bracket 1 and is apertured at 32 so that the shank 18 of the member 17 serves as a pivot for the ornament 306 as in the other embodiments. The body portion 33 50 of the ornament 306 extends downwardly at an angle and is provided with a plurality of spaced apertures 34. The loop 31 has a depression 35 formed therein to engage the connecting portion 21 of the member 17, so that the ornament 306 55 and the rod may be swung together as a unit. A plurality of cords or ropes 36 are fastened in spaced relation to the rod 23 by looping the cord therearound or by any other suitable means and the cords are then threaded through the openings 34 60 and the rod 23 as shown, while the free ends 37 of the cords 36 are allowed to hang downwardly. This creates a new and different treatment for windows and the particular treatment takes the 65 place of other forms of draperies. The ornament 306 and the rod 23 may be swung together as a unit as will be appreciated fully by those skilled in the art.

70 It will be seen that in all forms of the invention the bracket 1, the pivot member 17 and the rod 23 may all be made up as stock parts at a decreased cost because of the possibility of mass production. They are all of extreme simplicity, the bracket 1 being formed of ordinary metal 75 strap and the pivot member 17 being formed of

rod which is easily bent as desired and the rod 23 being formed of stock tubing. The ornaments may be made up in smaller numbers and when a particular ornament is desired it may be assembled with the other items and they may then be 5 sent out from the factory or if desired the ultimate purchaser may have several different ornaments for use with the same crane.

Having thus described my invention, what I claim as new and desire to secure by Letters Patent is:

1. In a curtain crane construction, the combination of a bracket comprising a pair of arms having vertically aligned apertures, a swinging sheet metal ornament having a portion fitted between said arms and apertured to register with the apertures of the bracket, said ornament having the end adjacent the bracket turned back to form a return adapted to swing between the bracket arms when the free end of the crane is 15 swung outwardly and having its free end bent back and apertured to receive and be supported by the free end of a curtain rod, means on said return to support a curtain return, a pivot member having a vertical shank fitting through the 20 apertures of the bracket and the apertured portion of the ornament fitted between said arms and having a downwardly offset horizontal portion, and a hollow rod extending through the aperture at the free end of the ornament and 25 fitting on the horizontal portion of said pivot member.

2. In a curtain crane construction, the combination of a bracket comprising a pair of arms having vertically aligned apertures, a swinging 35 sheet metal ornament having a portion fitted between said arms and bearing on the lower one thereof and apertured to register with the apertures of the bracket, said ornament having the end adjacent the bracket turned back to form a 40 return adapted to swing between the bracket arms when the free end of the crane is swung outwardly and having its free end bent back and apertured to receive and be supported by the free end of a curtain rod, a pivot member having a 45 vertical shank fitting through the apertures of the bracket for pivotal movement therein and fitting through the apertured portion of the ornament fitted between said arms and concealed by said ornament and serving as a pivot therefor 50 and having a downwardly offset horizontal portion disposed behind said ornament, and a rod 55 extending through the aperture at the free end of the ornament and supporting the same and fitting on the horizontal portion of said pivot member and supported thereby.

3. In a curtain crane construction, the combination of a bracket comprising a pair of arms having vertically aligned apertures, a swinging ornament having a portion fitted between said 60 arms and apertured to register with the apertures of the bracket, said ornament having the end adjacent the bracket turned back to form a return adapted to swing between the bracket arms when the free end of the crane is swung 65 outwardly, means on said return to support a curtain return, a rod having a vertical shank extending through the apertures of the bracket and the apertures of the ornament and having a downwardly offset horizontal portion extending 70 behind said ornament, and means extending from said rod to said ornament whereby the free end of said ornament is supported by the free end of said rod and may be swung with the rod 75 as a unit.

4. In a curtain crane construction, the combination of a bracket comprising a pair of arms having vertically alined apertures, a swinging ornament having a portion fitted between said arms and bearing on the lower one thereof and apertured to register with the apertures of the bracket, said ornament having the end adjacent to the bracket turned back to form a return adapted to swing between the bracket arms when the free end of the crane is swung outwardly, a rod having a vertical shank extending through the apertures of the bracket for pivotal movement therein and fitting through the apertures of the ornament and concealed by said ornament and serving as a pivot therefor and having a downwardly offset horizontal portion extending behind said ornament, and means extending from said rod to said ornament whereby the free end of said ornament is supported by the free end of said rod and may be swung with the rod as a unit.

5. In a curtain crane construction, the combination of a bracket comprising a pair of arms having vertically alined apertures, a swinging ornament having a portion fitted between said arms and bearing on the lower one thereof and apertured to register with the apertures of the bracket, a rod having a vertical shank extending through the apertures of the bracket for pivotal movement thereon and through the apertures of the ornament and concealed by said ornament and serving as a pivot therefor and having a downwardly offset horizontal portion extending behind said ornament, and means extending from said rod to said ornament whereby the free end of said ornament is supported by the free end of said rod and may be swung with the rod as a unit.

6. In a curtain crane construction, the combination of a bracket comprising a pair of arms having vertically alined apertures, a swinging ornament having a portion fitted between said arms and bearing on the lower one thereof and apertured to register with the apertures of the bracket, said ornament having the end adjacent to the bracket turned back to form a return adapted to swing between the bracket arms when the free end of the crane is swung outwardly, a rod having a vertical shank extending through the apertures of the bracket for pivotal movement therein and through the apertures of the ornament and concealed by said ornament and serving as a pivot therefor and having a downwardly offset horizontal portion extending behind said ornament, and means connecting said rod and ornament whereby they may be swung as a unit.

7. In a curtain crane construction, the combination of a bracket comprising a pair of arms having vertically alined apertures, a swinging ornament having a portion fitted between said arms and bearing on the lower one thereof and apertured to register with the apertures of the bracket, a rod having a vertical shank extending through the apertures of the bracket for pivotal movement therein and through the apertures of the ornament and concealed by said ornament and serving as a pivot therefor and having a downwardly offset horizontal portion extending behind said ornament, and means connecting said rod and ornament whereby they may be swung as a unit.

8. In a curtain crane construction, the combination of a bracket comprising a pair of arms having vertically alined apertures, a swinging ornament having a portion fitted between said

arms and bearing on the lower one thereof and apertured to register with the apertures of the bracket, a rod having a vertical shank extending through the apertures of the bracket for pivotal movement therein and through the apertures of the ornament and concealed by said ornament and serving as a pivot therefor and having a downwardly offset horizontal portion extending behind said ornament and concealed thereby.

9. In a curtain crane construction, the combination of a bracket comprising a pair of arms having vertically alined apertures, and a rod having a vertical shank extending through the apertures of the bracket and having a downwardly offset horizontal portion extending substantially centrally from said bracket.

10. In a curtain crane construction, the combination of a bracket comprising a pair of arms having vertically alined apertures, a swinging ornament having a portion fitted between said arms and bearing on the lower one thereof and apertured to register with the apertures of the bracket, said ornament having the end adjacent to the bracket turned back to form a return adapted to swing between the bracket arms when the free end of the crane is swung outwardly, a rod having a vertical shank extending through the apertures of the bracket for pivotal movement therein and through the ornament and serving as a pivot therefor, and having a substantially short horizontal portion extending from the top thereof, and a relatively long horizontal portion downwardly offset from said short horizontal portion and connected thereto by a substantially vertical connecting portion, a notch in the portion of said ornament which is fitted between said bracket arms, said vertical connecting portion of said rod fitting in and engaging said notch whereby said rod and ornament are held in relatively fixed position to one another whereby said rod and ornament pivot about said shank as a unit.

11. In a curtain crane construction, the combination of a bracket comprising a pair of arms having vertically alined apertures, a swinging ornament having a portion fitted between said arms and bearing on the lower one thereof and apertured to register with the apertures of the bracket, a rod having a vertical shank extending through the apertures of the bracket for pivotal movement therein and through the ornament and serving as a pivot therefor and having a substantially short horizontal portion extending from the top thereof and a relatively long horizontal portion downwardly offset from said short horizontal portion and connected thereto by a substantially vertical connecting portion, a notch in the portion of said ornament which is fitted between said bracket arms and said vertical connecting portions of said rod fitting in and engaging said notch whereby said rod and ornament are connected together and may be swung as a unit about the vertical shank of said rod.

12. In a curtain crane construction, the combination of a bracket comprising a pair of arms having vertically alined apertures, a swinging ornament having a portion fitted between said arms and bearing on the lower one thereof and apertured to register with the apertures of the bracket, a rod having a vertical shank extending through the apertures of the bracket for pivotal movement therein and through the ornament to serve as a pivot therefor and having a substantially short horizontal portion extending from the top thereof and a relatively long horizontal portion downwardly offset from said short hori-

5 horizontal portion, means on the portion of said ornament which is fitted between said bracket arms to engage said rod at a point spaced from its shank to hold said rod and ornament in relatively fixed position, said rod engaging said means whereby said rod and ornament are held together as a unit and may be swung about the vertical shank of said rod as a pivot.

13. In a curtain crane construction, the combination of a bracket comprising a pair of arms having vertically aligned apertures at their free ends, a swinging ornament comprising a strip having one end bent into a vertical loop and fitted between said arms and apertured vertically to register with the apertures in said arms and having its body portion extending downwardly at an angle from said bracket, said body portion having a plurality of apertures therealong spaced from one another, a rod comprising a pivot member having a vertical shank extending through the apertures of the bracket and the apertures of that loop of the ornament fitted within the bracket and having a substantially short horizontal portion extending from the top thereof and a relatively long horizontal portion downwardly offset from the short horizontal portion and connected thereto by a substantially vertical connecting portion, said rod adapted to support a plurality of ropes fastened to the horizontal portion thereof and spaced from one another and extending through the apertures in the body portion of said ornament with their ends hanging downwardly therefrom, and a depression formed in the edge of the loop of said ornament fitted in said bracket and engaging the vertical connecting portion of said rod whereby the rod and ornament may be swung as a unit.

14. In a curtain crane construction, the combination of a bracket comprising a pair of arms 40 having vertically aligned apertures at their free ends, a swinging ornament having an apertured portion fitted between said bracket arms and a body portion extending downwardly at an angle from the bracket and having a series of spaced 45 apertures therealong, a rod comprising a pivot member having a vertical shank extending through the apertures of the bracket and the apertures of that loop of the ornament fitted within the bracket and having a substantially short 50 horizontal portion extending from the top thereof and a relatively long horizontal portion downwardly offset from the short horizontal portion

and connected thereto by a substantially vertical connecting portion, said rod adapted to support a plurality of ropes fastened to the horizontal portion thereof and spaced from one another and extending through the apertures in the body portion of said ornament with their ends hanging downwardly therefrom, and a depression formed in the edge of the loop of said ornament fitted in said bracket and engaging the vertical connecting portion of said rod, whereby the rod and ornament may be swung as a unit.

15. In a curtain crane construction, the combination of a bracket comprising a pair of arms having vertically aligned apertures at their free ends, a swinging ornament having an apertured portion fitted between said bracket arms and a body portion extending downwardly at an angle from the bracket and having a series of spaced apertures therealong, a rod comprising a pivot member having a vertical shank extending through the apertures of the bracket and the apertures of that loop of the ornament fitted within the bracket and having a substantially short horizontal portion extending from the top thereof and a relatively long horizontal portion 25 downwardly offset from the short horizontal portion and connected thereto by a substantially vertical connecting portion, said rod adapted to support and a plurality of ropes fastened to the horizontal portion thereof and spaced from one another and extending through the apertures in the body portion of said ornament with their ends hanging downwardly therefrom.

16. In a curtain crane construction, the combination of a bracket comprising a pair of arms 35 having vertically aligned apertures at their free ends, a swinging ornament having an apertured portion fitted between said bracket arms and a body portion extending downwardly at an angle from the bracket and having a series of spaced 40 apertures therealong, a rod comprising a pivot member and having a vertical shank extending through the apertures of the bracket and the apertures of that loop of the ornament fitted within the bracket, said rod adapted to support 45 and a plurality of ropes fastened to the horizontal portion thereof and spaced from one another and extending through the apertures in the body portion of said ornament with their ends hanging downwardly therefrom.

GUY W. KIRSCH.
